UNITED STATES PATENT OFFICE.

HENRY J. KASCH, OF DAYTON, OHIO, ASSIGNOR TO THE KURZ-KASCH COMPANY, OF DAYTON, OHIO, A CORPORATION OF OHIO.

MOLDING PRESS.

Application filed May 1, 1922. Serial No. 557,537.

To all whom it may concern:

Be it known that I, HENRY J. KASCH, a citizen of the United States, residing at Dayton, in the county of Montgomery and State of Ohio, have invented certain new and useful Improvements in Molding Presses, of which the following is a specification.

This invention relates to molding presses, 10 and more particularly to that type of press in which the plastic material is softened by heat before the pressing operation, and thereafter cooled to harden it after the molding operation has been completed.

15 The principal object of my invention is to provide automatic means for drawing the knock-out pin plate outwardly or downwardly to effect the ejection of the finished product from the mold after the pressing operation is finished. Up to the present time it has been necessary to pry this plate down with a bar, which requires considerable time on the part of the operator and injures the plate. My improved means for 20 doing this comprise pull-back plungers which become operable to pull down the plate when the platen starts its descent after the molding operation is completed.

It is another object of my invention to 25 construct the ram cylinder and pull-back cylinder on each side of the machine, from a single casting.

Other important and incidental objects 30 will be brought out in the following specification and particularly set forth in the subjoined claims.

In the accompanying drawings, Figure 1 35 is a sectional, side elevation of the molding press with the die open. Figure 2 is a sectional, side elevation of the same with the die closed. Figure 3 is a side elevation of 40 the press. Figure 4 is a cross sectional view of the die, showing the pin bars, the knock-out pins and the knock-out pin plate. And Figure 5 is a top plan view, partly in section, of the ram and pull-back cylinder 45 castings, and supply lines.

Throughout the specification and drawings, similar reference characters denote corresponding parts.

Referring to the accompanying drawings 50 for a detailed description of one form of embodiment of my invention, the numeral 1 designates a pedestal base which supports a bed plate 2. Mounted upon the latter are

two upright cylinder blocks 4, 4 that have been cast to provide wide base portions that come to a taper at their inner ends. Projecting upwardly from the base portion of each block 4 is a ram cylinder 5 from whose 55 wall there projects outwardly an upright wing portion 6 containing an elongated bore 7 which receives a pull-back rod 8 having a plunger head 9. The cylindrical portion 5 of each block 4 contains an elongated bore 60 10 to receive a reciprocating ram 11. By so casting each of the blocks 4 to provide a ram cylinder and a pull-back cylinder in it, economy of construction and efficiency in 65 operation are obtained. (See Figures 1, 2 70 and 5.)

Mounted upon the rams 11, 11 is a platen 12 which supports a carrier block 13 for a steam-plate 14 whose top portion is recessed as shown in Figure 4 to receive mold-pin bars 15, 15. Projecting inwardly from the latter are horizontal pins 15^a, 15^a which engage the molded product from the side to assist in its ejection after the molding operation is completed. One type of product 80 to which the press is particularly adapted is a flanged telephone receiver which, after being molded, the pins 15^a, 15^a elevate when the mold-pin bars 15, 15 are engaged by the product-ejection means hereinafter to be 85 described. Between the mold-pin bars 15, 15 impression bars 16, 16 are disposed, the lower one being screwed to the steam-plate 14 and the upper one being screwed to a steam-plate 17 that depends from a carrier 90 or block 18 secured to a stationary platen or head 19. The latter has two laterally projecting wing or flange portions 20, 20 to which are bolted the head parts of two downwardly depending push-back cylinders 95 21, 21 respectively. Projecting into the lower end of each one of these cylinders 21 is a push-back plunger 22 whose lower end is connected to a flange portion 23 on the platen 12. The function of these plungers 100 22, 22 is to push the platen 12 and the rams 11, 11 down to their starting positions after a molding operation is completed. These plungers are operated by the pressure of a fluid which enters the tops of the cylinders 105 21, 21 through riser pipes 24, 24 respectively. (See Figures 1, 2, 3, 4 and 5.)

The fluid for raising the rams 11, 11 is delivered below them to the cylinders 10, 10 by branches 25, 25 of a pipe 26 to which 110

fluid is admitted by a three-way valve 27 from a pipe 28 connected to a main supply line 29. (See Figure 5.) Also connected to the main supply line is a lateral pipe 30 from which the two risers 24, 24 project and to which there are also connected branch pipes 31, 31 that conduct the fluid to the top portions of the pull-back cylinders 7, 7 respectively. (See Figures 1 and 5.)

- 10 The lower part of the carrier block 13 is grooved to receive a slotted pin plate 32 in such a manner that the latter may have an independent vertical movement with respect to the said carrier block. Each pull-back 15 rod 8 projects upwardly through a bushing 33 in the top of its respective cylinder 7, and through a hole in one side of the platen 12, for connection to one side of the pin plate 32, whereby, when the molding operation is finished, the fluid which enters the cylinder 7 will exert its pressure against the plunger-head 9 to pull the pin plate 32 downwardly. (See Figures 1 and 2.)

Extending upwardly from, and connected 25 to, the plate 32 is a series of knock-out pins 34 which, when the downward movement of the platen 12 is arrested, will engage the mold-pin bars 15, 15 to knock the molded product loose from the die. When the mold- 30 pin bars 15, 15 are so engaged, the horizontal pins 15^a, 15^a elevate the molded product by their firm grip upon it from the side, thus assisting in its ejection from the die. The descent of the platen 12 is arrested by the following means. Referring to Figures 1 and 2, pins 35, one of which is shown in each of those figures, project downwardly from the middle portion of the pin plate 32, through holes in the platen 12, for engagement with a slotted plate 36 mounted on the top portions of the cylinder blocks 4, 4. When the lower ends of the pins 35 strike this plate 36, the pin plate 32 will be held in a stationary position to cause the knock-out pins 34 to dislodge the molded articles as the platen 12 continues its downward movement.

The upper portion of the carrier block 18 is grooved like the carrier block 13, to receive a slotted pin plate 37 in such a manner that the latter may have an independent vertical movement with respect to the carrier block 18 and whose horizontal pins 15^a, 15^a raise the articles after said bars are so engaged. Secured to each end of the plate 37 is the upper end of a rod 38 which projects downwardly through a hole in the platen 12. Secured to the lower end of each rod 38 is a nut 39 which the platen 12, during its descent, is adapted to engage to pull the pin plate 37 downwardly to the position shown in Figure 1 after the molding operation is completed for the purpose of dislodging any molded articles that may 65 adhere to the top portion of the mold.

When the platen 12 again ascends, the pin plate 37 is pushed upwardly by the engagement of the ascending platen 12 with nuts 40, 40 on the rods 38, 38 respectively. (See Figure 2.) The molded articles which are 70 dislodged from the mold parts by the pin plates 32 and 37, are removed by the gloved hands of the operator after the press is opened for the discharge of them.

In operation, when it is desired to raise 75 the lower mold unit, the three-way valve 27 is turned to admit fluid to the pipe 26, from which it flows through the branch pipes 25, 25 to the cylinders 10, 10 respectively to elevate the rams 11, 11 within them. These 80 rams in turn raise the platen 12 to the pin plate 32, at which point the plastic material is inserted between the mold-pin bars 15, 15 and the impression bars 16, 16. The platen 12 and the members mounted on them 85 are then raised to compress the plastic material in the presence of the heat of the steam plates 14 and 17. During the ascent of the platen 12, it will raise the pin plate 32 with it, and until it comes in contact with the latter the tops of the knock-out pins 34 will be in their knock-out positions above the top of the recessed portion of the steam plate 14. Therefore, it is necessary for the platen 12 to reach the pin plate 32 before 90 the die part which it carries can be filled with the plastic material.

After the plastic material has been molded, the three-way valve 27 is turned to permit the fluid to flow out of the cylinders 10, 10, whereupon the platen 12 and the members carried by it are free to be pushed downwardly by the push-back plungers 22, 22. When the platen 12 starts its descent, the pin plate 32 will be drawn downwardly 100 by the pull-back rods 8, 8 until the pins 35 strike the stationary plate 36, at which time the descent of the pin plate 32 will be arrested to cause the knock-out pins 34 which project upwardly therefrom, to dislodge the 105 molded articles by engagement with the mold-pin bars 15 between which the latter articles have been formed. These molded 110 articles will be readily dislodged by the pins 34 because of the fact that after the platen 12 comes to the position where the downward movement of the pin plate 32 is arrested, it will continue its descent a sufficient 115 distance to draw the lower impression bar 16 below the molded articles whose 120 downward movement is restrained by the mold-pin bars 15 through their engagement with the knock-out pins 34.

It will now be seen that after the platen 12 starts its descent, the pull-back rods 8, 8 will draw the pin plate 32 downwardly 125 to its lowermost position without the necessity of prying it down to that point with a bar or other implement. Furthermore, these pull-back rods 8, 8 will also maintain or 130

hold the pin plate firmly against the platen 12 until the die part which it carries is filled with plastic material prior to another molding operation.

5 I do not wish to be limited to the details of construction and arrangement herein shown and described, and any changes or modifications may be made therein within the scope of the subjoined claims.

10 Having described my invention, I claim:

1. In a device of the type described, the combination with a base, of a platen movably supported thereon, a lower mold-part carried by said platen, an upper mold-part

15 supported above the lower one, elevating means for raising said platen to bring the lower mold-part into engagement with the upper one, a knock-out pin plate adapted to be carried upwardly by said platen, and

20 automatic means for pulling said knock-out pin plate downwardly when the platen starts its descent after the molding operation is completed.

2. In a device of the type described, the combination with a base, of a platen movably supported thereon, a lower mold-part carried by said platen, an upper mold-part supported above the lower one, means for raising said platen to bring the lower mold-part into engagement with the upper one, a knock-out pin plate adapted to be carried upwardly by said platen, and hydraulic means for pulling said knock-out pin plate downwardly when the platen starts its descent after the molding operation is completed.

3. In a device of the type described, the combination with a base, of a platen movably supported thereon, a lower mold-part carried by said platen, an upper mold-part supported above the lower one, means for raising said platen to bring the lower mold-part into engagement with the upper one, a knock-out pin plate adapted to be carried upwardly by said platen, means for arresting the downward movement of said pin plate before the platen reaches its lowermost position, pull-back cylinders, and plungers in said cylinders for pulling the said plate downwardly to the arresting means when the platen starts its descent after the molding operation is completed.

4. In a device of the type described, the combination with a base, of a cylinder casting mounted thereon, having a large bore and a small bore therein, a ram movable in the large bore, a platen supported by said ram, a lower mold-part carried by said platen, an upper mold-part mounted above the lower one, with which the lower mold-part is adapted to be carried into engagement by said platen, a knock-out pin plate adapted to be carried upwardly by said platen, and a plunger movable in the small bore in said cylinder casting for pulling said knock-out pin plate downwardly when the platen starts to descend after the molding operation is completed.

In testimony whereof I have hereunto set my hand this 28th day of April, 1922.

HENRY J. KASCH.
